UNITED STATES PATENT OFFICE.

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed August 18, 1922. Serial No. 582,818.

My invention relates to engine starters and more particularly to the drive or transmission between the starting motor and a member of the engine to be started, such as the flywheel thereof. My invention is shown and will be hereinafter described in connection with a well-known type of drive as exemplified in Bendix Patent No. 1,125,935 issued on January 26th, 1915. The object of my invention is to provide means whereby a maximum or over-all length of drive may be maintained independently of the usual drive spring, thereby maintaining a predetermined length of drive without interfering with the action of the drive spring with respect to its usual functions. Speaking in general terms, I accomplish this result by providing means such as a sleeve on the driving head and connecting such sleeve with one end of the rotatable member or screw shaft in such a manner as to permit of free rotary movement between such sleeve and shaft and also a limited longitudinal movement, one with respect to the other. By this connection between the shaft and sleeve, the outward longitudinal movement is limited or predetermined and the necessity for dependence upon the spring for the maintenance of maximum length of drive is eliminated.

In the drawing Fig. 1 is an elevation partly in section of a drive embodying my invention; Fig. 2 longitudinal section thereof; Fig. 3 an end view of the engaging end of the sleeve; Fig. 4 a plan view thereof; Fig. 5 a perspective of the end of the sleeve shown in Fig. 4; Fig. 6 a section of a second sleeve cooperating with the first sleeve; and Fig. 7 a detail view of the outer end of the screw shaft.

While I have shown my invention in connection with a type of drive disclosed generally in said Bendix patent, it will be understood that my invention is not limited to that particular construction, which is selected for the purpose of a clear and definite description of such invention. Moreover, while I have shown my invention in connection with a drive of the type known as the inboard, it will be understood that it is equally applicable to the outboard type. Furthermore, while I have shown the driving member or pinion as made in two parts, such as a pinion proper and a control member or nut, it will be understood that the single structure pinion such as shown in said patent might be employed in so far as my invention herein is concerned.

As shown, the starting motor 1 has an extended armature shaft 2 on which the drive is mounted and to which it is secured. This drive comprises a screw shaft 3 on which is mounted a pinion proper marked 4 and a nut 5 cooperating therewith, a driving head 6 and a coiled drive spring 7 secured at its opposite ends to such driving head and to the driven head 8 of the screw shaft by means of the bolts or studs 9 and 10. The structure described is the usual well-known type of drive above mentioned. In view of the fact that distortion of the spring, such as results from the starting operation, tends to elongate it, the over-all length of the drive cannot be maintained except in so far as there is a tendency of the spring to maintain it, which however, gives a variable length due to different degrees of elongation of the spring.

In order to maintain a predetermined maximum length of drive, I provide the following means: To the driving head 6 I secure, preferably by the bolt 9, a sleeve which has a cylindrical base portion and a substantially conical upper portion. In practice, this sleeve has a cylindrical base portion 11 and a cylindrical upper or inner portion 12 joined by a conical portion 13. This sleeve is located within the coils of the drive spring and its upper or inner portion is adapted to be connected in peculiar manner to the outer end of the screw shaft. As shown in Figs. 3, 4 and 5, the sleeve is provided with an in-turned marginal flange 14 extending somewhat more than half the circumference of the sleeve and is also provided with a side slot 15 which enters behind the flange 14. The screw shaft is provided at its outer end with a circumferential flange 16, thereby forming between it and the driven head 8, a wide groove 17. This flange 16 is of a size as to enter the side slot 15 of the sleeve and to then take its position behind the flange 14 of such sleeve. This particular construction is required for the ready assembling of the sleeve and shaft and for the proper relative rotary movements of these parts and the relative longitudinal movement thereof. In order to hold the sleeve and shaft in their assembled position I employ suitable means

such as a second sleeve comprising a cylindrical portion 18 and a conical portion 19, sloping in a direction opposite that of the conical portion 14 of the first sleeve. This 5 second sleeve is secured to the screw shaft in suitable manner as by means of the bolt 10 which secures one end of the drive spring to the shaft.

After the sleeves and screw shaft have 10 been assembled as above explained, the drive spring is assembled by securing it to the shaft by passing the bolt 10 through its forward eye and through the second sleeve and securing it into the shaft. In case of an in- 15 board installation as herein shown, the drive, without the driving head 6 is placed upon the armature shaft, and the sleeve 11 is pushed forwardly onto the shaft in order to 20 make room for the insertion of the usual key 20 which in addition to the screw 9 secures such head and armature shaft together. The driving head 6 is thereupon pushed along the armature shaft and over the key 25 and the bolt 9 thereupon inserted through the other eye of the spring and through the sleeve 11 and screwed into the driving head 6. In case of an outboard installation the 30 assembly is somewhat different. In this case the driving head 6 is placed on the armature shaft in usual manner and the remainder of the drive is placed on the armature shaft and the screw hole in such head is lined up with the hole through the sleeve 11 and the eye of the drive spring. The 35 screw or bolt 9 is then inserted and screwed into the drive head.

In operation, the screw shaft is permitted 40 to move longitudinally in the usual and well-known manner, for purposes of meshing, thereby compressing the drive spring in the usual manner, at which time the sleeve 18 will slide upon the outer cylindrical portion 12 of the other sleeve. When the drive 45 spring deflects due to load, it tends to elongate, which would increase the length of the drive except for the construction of the first mentioned sleeve and the screw shaft, inasmuch as such lengthening or elongation is 50 prevented by contact of the flanges 14 and 16.

When the drive spring deflects due to 55 torque in cranking the engine, space is provided for such spring to wrap down, such space being provided in the present instance by providing the two sleeves with the beveled or conical portions.

I claim:—

1. An engine starter drive formed as a 60 unitary structure including a rotatable member, a driving head, said head and rotatable member having a relative movement inwardly toward and outwardly away from each other, a drive spring between such head and rotatable member, and means constituting a 65 part of said unitary structure and adapted

to limit said outward movement of the head and rotatable member to the normal extended length of the drive.

2. An engine starter drive including a rotatable member, a driving head, said head and rotatable member having a relative movement inwardly toward and outwardly away from each other, a drive spring between such head and rotatable member, and means for limiting said outward movement of the head and rotatable member, said means comprising an element cooperating with said head and rotatable member, the latter having a limited sliding movement with respect to said element. 70

3. An engine starter drive including a rotatable member, a driving head, said head and rotatable member having a relative movement inwardly toward and outwardly away from each other, a drive spring between such head and rotatable member, and means for limiting said outward movement of the head and rotatable member, said means comprising a sleeve secured fixedly to the head and loosely to the rotatable member. 75

4. An engine starter drive including a rotatable member, a driving head, said head and rotatable member having a relative movement inwardly toward and outwardly away from each other, a drive spring between such head and rotatable member, and means for limiting said outward movement of the head and rotatable member, said means comprising a sleeve secured fixedly to the head and loosely to the rotatable member and having a detachable connection at its inner end which limits the outward movement of the sleeve and rotatable member, one with respect to the other. 85

5. An engine starter drive formed as a unitary structure including driving and driven elements, a torsion spring connecting between the two elements, said elements being movable towards and away from each other, and means constituting a part of said unitary structure and adapted to normally maintain a maximum distance of separation between said elements. 95

6. An engine starter drive including driving and driven elements, a torsion drive spring connecting between the two elements, said elements being movable towards and away from each other, and means for maintaining a maximum distance of separation between the elements, said means comprising a sleeve secured to one of the elements and loosely connected with the other element to permit limited axial movement of one of the elements with respect to the other element. 100

7. An engine starter drive including a rotatable member, a driving head, said head and rotatable member having a relative movement inwardly toward and outwardly 110

- away from each other, a drive spring between such head and rotatable member, and means for limiting said outward movement of the head and rotatable member, said 5 means comprising a sleeve secured fixedly to the head and loosely and detachably connected with the rotatable member to permit limited axial movement of the rotatable member with respect to said head, and a second sleeve secured to the rotatable member and telescoping with the first sleeve and preventing disengagement of the latter with the rotatable member. 50
10. 8. An engine starter drive including a rotatable member, a driving head, said head and rotatable member having a relative movement inwardly toward and outwardly away from each other, a drive spring between such head and rotatable member, and means for limiting said outward movement of the head and rotatable member, said means comprising a sleeve secured to the head and provided at one end with a flange 15 for a portion of its circumference and with a side slot adjacent such flange, said rotatable member having a flange adapted to enter the adjacent end of the head through its side slot. 60
15. 9. An engine starter drive including a rotatable member, a driving head, said head and rotatable member having a relative movement inwardly toward and outwardly away from each other, a drive spring between such head and rotatable member, and means for limiting said outward movement of the head and rotatable member, said means comprising a sleeve secured to the head and provided at one end with a flange 20 for a portion of its circumference and with a side slot adjacent such flange, said rotatable member having a flange adapted to enter the adjacent end of the sleeve through its side slot, and means for preventing disengagement of the sleeve and rotatable member after being assembled. 65
20. 10. An engine starter drive including a rotatable member, a driving head, said head and rotatable member having a relative movement inwardly toward and outwardly away from each other, a drive spring between such head and rotatable member, and means for limiting said outward movement 70
25. of the head and rotatable member, said means comprising a sleeve secured fixedly to the head and loosely and detachably connected with the rotatable member to permit limited axial movement of the rotatable member with respect to said head, and a second sleeve secured to the rotatable member and telescoping with the first sleeve and preventing disengagement of the latter with the rotatable member. 75
30. 11. An engine starter drive including a rotatable member, a driving head, a coiled drive spring connecting such member and head, and two telescoping sleeves arranged within the spring and secured respectively to the member and head, and one of the sleeves being loosely connected with said member for relative endwise movement of the latter. 80
35. 12. An engine starter drive including a rotatable member, a driving head, a coiled drive spring connecting such member and head, and two telescoping sleeves arranged within the spring and secured respectively to the member and head, said rotatable member having at one end a circumferential groove, and the sleeve which is secured to the head having an end flange engaging said groove. 85
40. 13. An engine starter drive including a rotatable member, a driving head, a coiled drive spring connecting such member and head, and two telescoping sleeves arranged within the spring and secured respectively to the member and head, said sleeves having inwardly directed beveled portions to accommodate the spring coils when wrapped down. 90
45. 14. An engine starter drive including a rotatable member, a driving head, a coiled drive spring connecting such member and head, and two telescoping sleeves arranged within the spring and secured respectively to the member and head, one of the sleeves having a reduced shell portion on which the other sleeves slide and both sleeves having beveled portions directed towards each other 95
